FABRIC COVERED EYELET BUTTON

William Novick, Brooklyn, N. Y.

Application August 19, 1950, Serial No. 180,487

4 Claims. (Cl. 24—113)

1

This invention relates to new and useful improvements in fabric covered eyelet buttons such as those disclosed in my prior Patent No. 2,264,185, issued November 25, 1941, and a machine for the assembly of such buttons.

One object of the invention is the provision in a fabric coated button of means for securing the fabric covering on the formed face of a rigid supporting member in a smooth attractively appearing manner.

Another object of the invention is to construct and arrange the said means so that the same is most effective at the points of change of direction of the formation of the face of said supporting member.

Still another object of the invention is to construct said means so that the same is extremely simple in its use and manufacture and thus is an economical asset in the manufacture of fabric covered buttons.

A further object of the invention is the provision of a simple and effective apparatus for securing the fabric covering of the rigid supporting means.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of an exemplification of the improved button of the invention.

Fig. 2 is an enlarged sectional view on line 2—2 of Fig. 1.

Fig. 3 is an enlarged plan view of the rigid supporting member of the button.

Fig. 4 is an exploded perspective view of the several components of the button.

Fig. 5 is a fragmentary sectional view similar to Fig. 2 but illustrates a modified form of the invention.

Fig. 6 is a fragmentary sectional view similar to Fig. 3 but illustrating the modified means of Fig. 5.

Fig. 7 is a fragmentary sectional view similar to Fig. 2 but illustrating another modified form of the invention.

Fig. 8 is a fragmentary view on the same line as Fig. 7 but illustrates a step in the assembly of the button.

Fig. 9 is a plan view similar to Fig. 3 but illustrates the modified means of Figs. 7 and 8.

Fig. 10 is a side elevation on a large scale, of

2

apparatus for securing the fabric covering on the rigid support member.

Fig. 11 is an enlarged fragmentary sectional view on line 11—11 of Fig. 10.

Fig. 12 is an enlarged fragmentary sectional view on line 12—12 of Fig. 10.

Referring to Figs. 1—4 there is illustrated one preferred embodiment of the button of the invention. As shown, the button comprises a fabric covering 10, a layer of adhesive thermoplastic material 11, a rigid supporting member 12 and a backing or clamp member 13.

Preferably the supporting member 12 is of metal or similar material and comprises a disc having a peripheral flange 14 which extends from a raised roll or bead 15 at the peripheral limit of the disc. Centrally of member 12 there are provided a pair of holes 16 through which are passed the shanks of a pair of eyelets 17 as will be more fully described hereinafter.

Immediately within the raised roll 15 the disc of the support member is provided with a ring of holes 18 each having a rounded rectangular outline. The purpose of the holes 18 will be described presently.

The fabric covering 10 may be of any suitable sort and is provided in the form of a substantially circular patch of the desired size.

The adhesive material used preferably is of the type available in sheets which become tacky or adhesive on the application of heat thereto. Here also a substantially circular patch is provided, the patch being sufficiently large to cover the entire outer surface of member 12.

In forming the button the adhesive patch 11 and the fabric patch 10 are laid against the member 12, and by means of a suitably formed heating iron are pressed smooth thereagainst. The heat of the iron causes the patch 11 to adhere both to the member 12 and also to the patch 10.

The point at which the greatest strain is placed on the adherence of patch 11 to member 12 is at the inner peripheral base of the raised roll 15 and it is to prevent disengagement of the two components at this point that the ring of holes 18 is provided. As best shown in Fig. 2, a portion of the adhesive material is extended through each hole 18 and, in effect, forms a rivet 20 which securely grips the member 12.

Once the fabric cover 10 is secured in place the ends thereof are turned up within the flange 14 and the clamp member 13 is secured in place. As shown, member 13 comprises a disc with a peripheral flange which fits tightly within the flange

14 and secures the turned in ends of the fabric cover 10 in place.

The member 13 is provided with a pair of holes 21 which are aligned with the holes 16 in member 12. Finally, therefore, the fabric and adhesive patches 10 and 11 are pierced and the eyelets 17 are inserted through the holes 16 and 21 in members 12 and 13 not only to secure the two together but also to provide channels for sewing the button on a garment or the like.

It will be seen, therefore, that in the finished fabric covered button the fabric cover faithfully conforms to the desired configuration of the rigid support member.

A modified form of the invention is illustrated in Figs. 5 and 6 wherein like parts are given the same reference numerals as hereinabove with a prime added. The ring of holes 18 is replaced by a ring of holes 23 each having a countersunk sharply angularly figure eight outline. By means of their shape and the countersinking thereof, the holes 23 are adapted to provide a firmer bond between the fabric cover 10' and the supporting member 12', even though the amount of extruded adhesive material 11' is small. Further, the shape of the holes 23 provides a firmer bond against relative sliding or twisting movements between the parts. The remainder of the button is the same as described above.

Another modified form of the invention is illustrated in Figs. 7, 8 and 9 wherein like parts are given the same reference numerals as hereinbefore with a double prime added. In this form of the invention the ring of holes in the disc portion of the support member is replaced by a narrow mouthed channel 24 formed at the inner base of the raised peripheral roll or bead 15''. As best shown in Fig. 8, the adhesive patch 11'' is doubled on itself and inserted into said channel so that when heat is applied thereto the same becomes anchored in the channel throughout the entire periphery of the disc portion of member 12''. It will be seen, therefore, that the fabric cover 10'' is tightly secured in place in conformity to the configuration of member 12. The remainder of the button may be the same as described above.

Referring now to Figs. 10-12 there is disclosed therein a device for securing the fabric cover on the rigid support member. Said device comprises a tube or rod 26 having its lower end securely imbedded in or otherwise fastened to a table top 27. As shown the tube or rod has a hollow reduced upper end 28 which is threaded externally to have removably secured thereon a cap member 30 adapted to act as a heating iron. To apply heat to the cap 30, an electrical heating unit 31 enclosed within a casing of steel is mounted in the reduced portion 28 and may have its power leads 32 extending downward through tube 26 to a convenient source of electrical energy.

A spring 33 coiled about the base of tube 26 supports a cylindrical housing 34 slidable up and down on the latter. The housing 34 consists of a base plate 35, a peripheral wall 36, and a cover plate 37. The base plate 35 is provided with a central opening surrounded by a flange 38 which bears on tube 26.

As shown, the spring 33 engages the base plate 35 and in the normal position of the housing maintains the upper edge of flange 38 against an annular collar 40 of the tube. Adjacent the periphery thereof the upper face of base plate 35 is provided with an annular groove 41 in which the lower edge of wall 36 is fitted.

The wall 36 is preferably formed of wood and is provided with a series of vertical slots or vents 42 adapted to ventilate the interior of the housing and prevent overheating thereof by the heater unit 31. At its upper end the wall is fitted into an annular groove 43 in the under face of cover plate 37.

The cover plate 37 is provided with a central opening 44 into which the cap member 30 above described is adapted to fit snugly. The opening 44 is surrounded by a flange 45 having a rounded upper edge adapted to be engaged by the roll portion 15 of the rigid support member 12. When the said roll portion is engaged over the flange 45, as shown in Fig. 11, the same is securely seated in place.

As clearly shown in Figs. 10 and 11, the cap member 37 is comprised of superimposed sections comprising a lower section 37^a rested on the top of the housing 34 and a top section 37^b. The top face of the lower section 37^a is formed with a concentric upwardly extending projection 37^c which is externally threaded and received within a complementary threaded recess formed in the bottom face of the top section 37^b releasably joining the sections together. About its periphery, adjacent the bottom face of the top section 37^b, the top section is formed with a plurality of notches 37^d by which a grip can be had on the top section 37^b for unscrewing the sections to separate the same. Thus, the top section 37^b of the cover plate and the cap 30 are removable to be interchanged with other top sections and caps for assembling buttons of different sizes.

The device also includes a male die member 46 adapted to be pressed downward against the central portion of support member 12, such pressing lowering the housing 34 until the cap member 30 is engaged within the opening 44 and against the under side of the support member. The die member 46 is provided with an undercut peripheral edge 47 adapted to the roll 15 of member 12, and is threaded onto the lower end of a tube or rod 48. Said tube is slidably mounted in a loop 49 formed at the free end of the horizontal arm of a support 50 which is secured to table top 27 by means of bolts passed through feet 51 thereof.

Preferably the die member 46 is depressed by lever system culminating in a foot treadle. Such systems are extremely familiar, however, and it is deemed necessary only to illustrate the preferred means for connecting a said system to the tube 48, the remainder of the system being shown diagrammatically. As shown, a rod 52 is passed transversely through the tube 48 near the upper end thereof and engages in slots 53 in the arms 54 of a yoke formed by spreading the ends of a pair of lever arms 55 which are secured together throughout their lengths by bolts 57. The levers 56 are suitably pivoted at their other ends and are connected by a suitable pull link 58 with an ordinary foot treadle 60.

The operation of the device consists in placing the support member 12 on the flange 45, placing an adhesive sheet 11 and a fabric sheet 10 thereabove, and depressing the die member 46 by means of the treadle 60. The die is maintained depressed until the pressure and the heat from unit 31 secure a firm bond between fabric 10 and member 12.

It is to be noted that the just described device is readily adjustable to handle buttons of any desired size and shape by interchanging the cap member 30, the top section 37^b of the cover plate

37 and the die member 46, for others of the correct configuration.

A peripheral notch 61 is to provide a convenient lifting means for the fabric 10 from the cover plate 37.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A fabric covered button which comprises a rigid supporting member of circular outline having a central disc-like portion surrounded by a raised bead from which a peripheral flange depends, a ring of holes in said disc-like portion immediately adjacent said bead, each said hole being of angular figure eight outline and being countersunk, a layer of adhesive material adhering to the surface of said member with portions thereof extruded through said holes, a fabric cover secured to said adhesive and extending up within said flange, a clamp member having a flange tightly engaged within the first said flange, aligned holes in said fabric cover, said support member, and said clamp member, and an eyelet engaged in each said latter hole.

2. A fabric covered button which comprises a rigid supporting member of circular outline having a central disc-like portion surrounded by a raised bead from which a peripheral flange depends, a ring of holes in said disc-like portion immediately adjacent said bead, each said hole being of angular figure eight outline and being countersunk, a layer of adhesive material adhering to the surface of said member with portions thereof extruded through said holes, a fabric cover secured to said adhesive and extending up within said flange, a clamp member having a flange tightly engaged within the first said flange, aligned holes in said fabric cover, said support member, and said clamp member, and an

eyelet engaged in each said latter hole, whereby the portions of the adhesive material extruded through the holes of the ring form rivets to more securely bind the fabric cover to the disc-like portion of the support member immediately adjacent said bead.

3. The combination of claim 1 wherein said adhesive includes a depending flange between the peripheral flange and downward portion of the fabric to bond securely the fabric material and rigid support to provide a permanent fabric covered button.

4. A fabric covered button which comprises a rigid supporting member of circular outline having a central disc-like portion surrounded by a raised bead from which a peripheral flange depends, a ring of holes in said disc-like portion immediately adjacent said bead, each said hole being of angular figure eight outline and being countersunk, a layer of adhesive material adhering to the surface of said member with portions thereof extruded through said holes, a fabric cover secured to said adhesive and extending up within said flange, a clamp member having a flange tightly engaged within the first said flange, and means securing said clamp and fabric covered button together.
